UNITED STATES PATENT OFFICE

2,642,271

WATER HEATER

Jack Berger, Laurelton, N. Y., assignor to Diesel
Oil Burner Corp. of N. Y., Jamaica, N. Y.

Application October 21, 1948, Serial No. 55,738

3 Claims. (Cl. 257—252)

1

My present invention relates to water heaters, and more particularly to connecting means for connecting the open ends of consecutive pairs of water tubes with each other.

It is an object of my present invention to provide connecting means which are adapted not only for connecting one pair of water tubes but adapted to connect a plurality of pairs of water tubes with each other in such a manner that the tubes forming each consecutive pair of tubes are connected with each other but that each pair of connected tubes is independent and divided from the preceding and following pairs of tubes.

It is another object of my present invention to provide connecting means which are simple in construction and manufacture.

Finally, it is also an object of my present invention to provide unitary connecting means for a great number of tubes which are inexpensive to manufacture.

With the above objects in view, my present invention mainly relates to a water heater provided with a plurality of parallelly arranged water tubes and connecting means for connecting the open ends of consecutive pairs of these tubes with each other; as proposed by me, these connecting means comprise in combination a longitudinal connecting member having a U-shaped cross section being substantially hollow from one end thereof to the other and having a flat top face facing the open ends of the water tubes, a row of round openings in the flat top face of the longitudinal connecting member arranged at a small distance from each other in longitudinal direction of the longitudinal connecting member so that each of the plurality of water tubes is adapted to fit into one of the round openings and to be water-tightly secured therein; and a plurality of dividing walls arranged within the longitudinal connecting member in transversal direction in such a manner as to form within the longitudinal connecting member compartments each of which communicates with one of the consecutive pairs of the water tubes.

In accordance with a preferred embodiment of my present invention, the new connecting means comprise a longitudinal channel member being open at its top and having two lateral top edges, a longitudinal cover strip water-tightly secured along its edges to the lateral top edges of the longitudinal channel member, a row of openings in the longitudinal cover strip arranged at a slight distance from each other in longitudi-

2

nal direction of the longitudinal cover strip so that each of the plurality of water tubes is adapted to fit into one of the openings and to be secured water-tightly within the same, and a plurality of dividing walls arranged within the longitudinal channel member in transversal direction of the same spaced from each other in such a manner as to form within the longitudinal channel member consecutive channel compartments water-tightly divided from each other and having each of such a length as to communicate with two consecutive openings in the longitudinal cover strip.

The novel features which I consider as characteristic for my invention are set forth in the appended claims. The invention itself, however, both as to its construction and its method of operation, together with additional objects and advantages thereof, will be best understood from the following description of a specific embodiment when read in connection with the accompanying drawings, in which:

Fig. 1 is a perspective view of a part of a water heater according to my present invention; and

Fig. 2 is a longitudinal sectional view on line 2—2 in Fig. 1.

In the water heater arrangement shown in Figs. 1 and 2, the water tubes 10 are arranged parallel to each other. The connection between the tubes of consecutive pairs of water tubes is obtained by the connecting channel-shaped member 26.

This channel-shaped member 26 is simultaneously covered and subdivided by the combined cover and dividing strip 27 which has top portions 28 and downwardly bent dividing portions 29. The end walls 30 are also bent out of strip 27. The edges of the strip 27 are firmly brazed to the channel member 26 so as to form separate compartments 31. The channel-shaped member 26 includes two side wall portions 25 which are substantially parallel, and a connecting wall portion 24.

Each of the top portions 28 of strip 27 is provided with two holes 32 into which fit the water tubes 10 as indicated in dotted lines. Each pair of water tubes 10 communicates through one compartment 31.

It should also be stressed that although I have described above my new connecting means only as adapted for connecting heater tubes in a water heater, the same might also be used for connecting other types of tubes, e. g. tubes through which gases or air are passing.

It will be understood that each of the elements described above, or two or more together, may also find a useful application in other types of connecting devices, differing from the types described above.

While I have illustrated and described the invention as embodied in water heaters, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention, and, therefore, such adaptations should and are intended to be comprehended within the meaning and range of equivalence of the following claims.

What I claim as new and desire to secure by Letters Patent is:

1. In a water heater provided with a plurality of parallelly arranged water tubes, connecting means for connecting the open ends of the tubes of consecutive pairs of said water tubes with each other, said connecting means comprising in combination a longitudinal channel member including two side wall portions extending substantially parallel to each other through the entire length of said channel member and having two top edges, and a connecting wall portion integral with said side wall portions and connecting the same along the entire length of said channel member, said channel member being open at its top and at its opposite ends; a longitudinal cover strip water-tightly secured along its edges to said top edges of said side wall portions of said longitudinal channel member; a row of openings in said longitudinal cover strip arranged at a slight distance from each other in longitudinal direction of said longitudinal cover strip so that each of said plurality of water tubes is adapted to fit into one of said openings and to be secured water-tightly within the same; a plurality of consecutive bends in said longitudinal cover strip forming a plurality of transversal walls extending normal to the direction of said longitudinal cover strip and reaching into said longitudinal channel member in such a manner as to form within said longitudinal channel member consecutive channel compartments water-tightly divided from each other and having each such a length as to communicate with two consecutive openings in said longitudinal cover strip.

2. In a water heater provided with a plurality of parallelly arranged water tubes, connecting means for connecting the open ends of the tubes of consecutive pairs of said water tubes with each other, said connecting means comprising in combination a longitudinal channel member including two side wall portions extending substantially parallel to each other through the entire length of said channel member and having two top

edges, and a connecting wall portion integral with said side wall portions and connecting the same along the entire length of said channel member, said channel member being open at its top and at its opposite ends; a longitudinal cover strip provided with a plurality of consecutive bends forming bent transversal wall portions extending normal to the plane of said longitudinal cover strip, said thus bent longitudinal cover strip being water-tightly secured along its edges to said top edges of said side wall portions of said longitudinal channel member so that said bent transversal wall portions reach into said longitudinal channel member dividing the same into a plurality of consecutive channel compartments water-tightly divided from each other; and a row of openings in said longitudinal cover strip arranged in longitudinal direction thereof in such a manner that each strip portion between two consecutive bends is provided with two openings.

3. In a water heater provided with a plurality of parallelly arranged water tubes, connecting means for connecting the open ends of the tubes of consecutive pairs of said water tubes with each other, said connecting means comprising in combination a longitudinal channel member including two side wall portions extending substantially parallel to each other through the entire length of said channel member and having two top edges, and a connecting wall portion integral with said side wall portions and connecting the same along the entire length of said channel member, said channel member being open at its top; a longitudinal cover strip provided with a plurality of consecutive bends forming bent transversal wall portions extending normal to the plane of said longitudinal cover strip, said thus bent longitudinal cover strip being water-tightly secured along its edges to said top edges of said side wall portions of said longitudinal channel member so that said bent dividing wall portions reach into said longitudinal channel member dividing the same into a plurality of consecutive channel compartments water-tightly divided from each other; a row of openings in said longitudinal cover strip arranged in longitudinal direction thereof in such a manner that each strip portion between two consecutive bends is provided with two openings; and end walls at both ends of said longitudinal channel member secured to the end edges of the same and of said longitudinal cover strip water-tightly closing the open ends of said longitudinal channel member.

JACK BERGER.
